UNITED STATES PATENT OFFICE

PIERRE J. CHÉRON, OF STRATFORD, CONNECTICUT, ASSIGNOR TO MOTOMETER GAUGE & EQUIPMENT CORPORATION, OF LONG ISLAND CITY, NEW YORK, A CORPORATION OF DELAWARE

DESIGN FOR A MEDALLION

Application filed December 2, 1929. Serial No. 33,621. Term of patent 14 years.

To all whom it may concern:

Be it known that I, PIERRE J. CHÉRON, a citizen of the United States, residing in Stratford, county of Fairfield and State of Connecticut, have invented a new, original, and ornamental Design for a Medallion, of which the following is a specification, reference being had to the accompanying drawing forming a part thereof.

Figure 1 is a front elevation of a medallion embodying the present design;

Figure 2 is a side elevation of the medallion; and

Figure 3 is a plan view of the same.

The medallion as illustrated is adapted to be used upon the front of an audible traffic warning device to ornament the face thereof.

I claim:

The ornamental design for a medallion substantially as shown and described.

PIERRE J. CHÉRON,
